UNITED STATES PATENT OFFICE.

EDWARD C. BERNERS, OF TWO RIVERS, WISCONSIN.

FOUNTAIN PENCIL.

Application filed June 26, 1922. Serial No. 571,102.

To all whom it may concern:

Be it known that I, EDWARD C. BERNERS, a citizen of the United States, and resident of Two Rivers, in the county of Manitowoc 5 and State of Wisconsin, have invented certain new and useful Improvements in Fountain Pencils; and I do hereby declare that the following is a full, clear, and exact description thereof.

10 My invention refers to fountain pencils for the distribution of fluids, such as glue, or the like.

The primary object of my invention is to simplify the construction of such pencils, 15 whereby the filling opening in the hollow stem thereof is dispensed with and the distributing end of the pencil is utilized for both filling and distribution of the fluid.

Another object of my invention is to provide a sleeve for closing the distributing end 20 of the pencil, which sleeve carries various types of distributing nozzles to be selectively used.

Another object of my invention is to provide the closure sleeve with exteriorly 25 tapered walls having a resilient surface thereon for engagement with the lip of the stem distributing opening, said opening back of the lip being provided with an ex-

30 pansion chamber or cavity, whereby the sleeve, which is in the form of a cork, will be firmly held against displacement when the pencil is in use to thus prevent leakage.

Another object of my invention is to provide a hollow pencil stem having a closed 35 end, and an open distributing and filling end, the lips about the open end being merged into an expansion chamber back of the stem, whereby a slight cavity is formed 40 between the sleeve or core and the juxtaposed walls of the filling end to produce a suction chamber, thereby preventing accidental discharge of the cork.

Another object of my invention is to provide the cork or closure sleeve with various 45 forms of distributing nozzles to meet the requirements of the trade.

A further object is to provide the hollow 50 stem with corresponding diameter shouldered collars at its ends for selective engagement with a thimble, which thimble can be nested over the filling opening parts, when the pencil is not in use, to protect the same, and it can be adjusted over the closed end 55 of the stem to lengthen said stem when the instrument is in use.

Another object of my invention is to form the hollow stem of the pencil from such substance as hard rubber, whereby accuracy is obtained and the life of the stem body is 60 thus increased.

With the above and other minor objects in view, the invention consists in certain peculiarities of construction and combination of parts, as are hereinafter set forth 65 with reference to the accompanying drawings and subsequently claimed.

In the drawings:—

Figure 1 is a sectional elevation of a fountain pencil embodying the features of my 70 invention, the same being shown equipped with a closure sleeve and mucilage distributing nipple, which nipple forms the nozzle part that is associated with the sleeve.

Figure 2 represents a fragmentary view 75 of the pencil stem and closure therefor, the closure being formed integral with a pointed nozzle having a flexible air dome associated therewith, and

Figure 3 is a similar sectional view showing 80 the distributing end of the pencil equipped with a porous nozzle in conjunction with the closure sleeve, whereby fluids, such as water, can be distributed from the pencil body. 85

Referring by characters to the drawings, 1 represents a hollow body or stem, preferably formed from one piece of hard rubber, having a closed end 2 and an open distributing and filling end 3. The ends of the 90 pencil are formed with shouldered collars 4—4', which collars are of the same diameter and adapted to selectively receive a thimble 5 that is adjusted in position to close the discharge end of the pencil or add 95 length to the rear closing end thereof, the same being frictionally held.

The hollow body of the stem 1 is of slightly greater diameter than the under discharge end bore 1' and the discharge end 100 bore rearward of the mouth lips 3' is expanded slightly to form a chamber 6. The distributing mouth of the stem is closed by a stopper, preferably in the form of a sleeve 7, which sleeve may be composed of 105 hard rubber, or other fibrous material, and the outer wall of the stem is tapered inwardly and fitted with a soft rubber jacket 8, which jacket is expanded over an annular end bead 7', whereby it is more securely locked in position with relation to 110 the tapered surface of the sleeve.

As shown in Figure 1 of the drawings, the outer end of the membranous jacket 8 is continued to form a pliable distributing nozzle 9, the end of which is formed with 5 suitable apertures, whereby fluid contained in the stem will be discharged in the desired volume by the operator when pressure is put upon said nozzle.

Referring to Figure 2 of the drawings, 10 the body of the stopper or sleeve 7 is continued outwardly to form a rigid pointed nozzle 9', which nozzle, when not in use, is closed by a metallic pin 10 to thus prevent 15 clogging or gumming up of the mouth of the nozzle by the fluid when it is not in use. This form of nozzle is particularly used by 20 photographers or artists and it is formed with a rearwardly extended hollow neck 11, to which neck is fitted a closed rubber nipple 12 constituting a flexible air dome.

When this form of nozzle is in use, the operator, in manipulating the pencil, can, by pressure of the flexible air dome or nipple, create a forced draft through the nozzle, 25 whereby a positive spray is discharged therefrom, the nipple in its functioning being contracted and expanded alternately and this action can be effected by a pressure of one finger thereupon, so as not to interfere with proper manipulation of the pencil.

Referring now to Figure 3 of the drawings, the sleeve 7 is provided with a soft rubber jacket similar to that shown in connection with the other forms of my invention, except in this case the discharge end 30 of the jacket is contracted over the beaded end 7' of the sleeve to form a restricted discharge opening α , which opening is fitted with a sponge or other porous substance γ , whereby fluid contained in the body of the pencil can be distributed; as for example, in some cases the pencil may be used for water or other fluid and can be used for the purpose of affixing stamps, or moistening any 45 gummed surface.

It will be noted from the foregoing that in each instance the removable nozzle, which forms a closure or cork for the open discharge end of the same, is provided with a 50 tapered exterior wall covered by the flexible jacket. It is to be noted that the hollow barrel 1 is provided with a slightly tapered portion adapted to receive the inner end of the stopper and is provided with an expanded portion 3 in front of such tapered portion. Thereafter, this expanded portion contracts and forms a relatively inturned lip which also forms a contracting ring like member adapted to grip the stopper or its 55 membranous jacket and thus secures a firm hold thereon.

Heretofore, this closure problem has confronted all manufacturers of devices of this character and my present invention has 60 solved the problem of a secure closure,

whereby economy in manufacture is insured and whereby the pencil stem can be formed with a single opening, whereas, under ordinary conditions, it was necessary to form the stem having both ends open, one of which 70 was for the purpose of filling and necessarily to be corked with means for removal, rendering a liability of the corked end to become disarranged under ordinary office usage.

In practice, the pencil is sold with the combination stopper, as disclosed, and sold to the trade with an extra stopper, such as shown in Figure 1 of the drawings. The rubber tit or nipple of the stopper, under 80 ordinary usage, sometimes becomes gummed up by a surplus of glue or mucilage. In this case, the gummed stopper is removed quickly and can be cleansed by soaking it in water, which soaking will remove all the surplus glue and soften the rubber to thereby add life to it. When the gummed stopper is in the process of cleaning by soaking, the extra stopper supplied with the pencil is temporarily used and is inserted in the mouth of the hollow stem for immediate use. The extra stopper can then be used indefinitely and thereafter it can be replaced by the cleansed stopper, which had previously been 90 put into soak for renewal purposes.

While I have shown and described a simple exemplification of my invention minutely with reference to all of its details, it is understood that the shapes of the various parts and minor details of construction may 100 be varied within the scope of the appended claims.

I claim:—

1. A fountain pencil comprising a one piece hollow stem having a single opening 105 therein, said opening being formed by a contracted portion and having an enlarged portion immediately in front of said contracting portion, said enlarged portion terminating in an inturned edge, a closure having an aperture therethrough, a membranous jacket surrounding said closure and wedged between said closure and the contracted part and inturned lip.

2. A fountain pencil comprising a hollow barrel closed at one end and having an opening at the other end, a discharge member fitted within said opening and having a passageway therethrough gradually contracting towards its outer end, said discharge member having a laterally offset neck provided with a passageway communicating with said first mentioned passageway, and a flexible bulb connected with said neck.

In testimony that I claim the foregoing 125 I have hereunto set my hand at Two Rivers, in the county of Manitowoc and State of Wisconsin.

EDWARD C. BERNERS.
